Des. 183,816
Patented Oct. 28, 1958

183,816

FLYING AUTO

Howard M. Simmons, Rutledge, Pa.

Application June 27, 1957, Serial No. 46,756

Term of patent 14 years

(Cl. D14—3)

FIG. 1

FIG. 3.

FIG. 2.

Figure 1 is a perspective view of a flying auto;
Figure 2 is a top plan view of the flying auto of Figure
1; and

Figure 3 is a rear elevation view of the flying auto
of Figure 1.

The side of the flying auto not shown in Figure 1
is the same as the side shown in Figure 1 in appearance.

I claim:

The ornamental design for a flying auto, as shown and
described.
